[57] CLAIM

The ornamental design for a golf club grip, as shown
and described.

DESCRIPTION

FIG. 1 is an elevation view of the ornamental design for
a golf club grip.

FIG. 2 is a top view of the grip of FIG. 1.

FIG. 3 is a bottom view of the grip of FIG. 1.

FIG. 4 is a perspective view of the grip of FIG. 1 showing
a golf club shaft in broken outline over which the
grip may be fitted for illustrative purposes only.
